(57) **CLAIM**

The ornamental design for a tire, as shown and described.

DESCRIPTION

FIG. 1 is a side perspective view of a tire showing our new design, it being understood that the tread pattern is repeated throughout the circumference of the tire, the opposite side being the same as that shown;

FIG. 2 is a front elevational view thereof, the opposite side being identical thereto;

FIG. 3 is a side elevational view of the right side thereof; FIG. 4 is a side elevational view of the left side thereof; and, FIG. 5 is an enlarged fragmentary front elevational view thereof.

The broken lines in the drawings illustrate portions of the tire that form no part of the claimed design.
